FIG. 1

FIG. 2

FIG. 3

INVENTOR.
HENRY WILLIAMS
BY
Milton S. Crandall,
ATTORNEY.

UNITED STATES PATENT OFFICE.

HENRY WILLIAMS, OF CORRECTIONVILLE, IOWA.

VEHICLE-WHEEL.

1,290,452.

Specification of Letters Patent. Patented Jan. 7, 1919.

Application filed January 6, 1917. Serial No. 140,948.

To all whom it may concern:

Be it known that I, HENRY WILLIAMS, a citizen of the United States, and a resident of Correctionville, in the county of Woodbury and State of Iowa, have invented certain new and useful Improvements in Vehicle-Wheels, of which the following is a specification.

The present invention relates to vehicle wheels and wheels for other traveling structures.

The invention has for its primary object the production of a travel wheel embodying certain novel features of construction whereby the tendency to twist the axle shaft by rotation of the wheel is reduced to the minimum.

Another object of the invention is the production of a wheel of this character staple yet simple in construction and adapted to rotate with little loss of power.

With these and other objects in view, the invention consisting in the construction, combination and novel arrangement of parts will be fully understood from the following description, reference being had to the accompanying drawings which form a part of this application and in which like characters of reference indicate corresponding parts throughout the several views, of which,—

Figure 1 is an elevation of the inner face of a wheel constructed in accordance with the invention; Fig. 2 is a vertical section of the same; and Fig. 3 is a fragmentary plan of the spoke embracing band.

Although I have illustrated and herein-after described the preferred embodiment of the invention I would not be understood as being limited to the specific structure chosen for illustration for it is evident that various alterations and modification in the details of construction and arrangement of parts may be made without departing from the spirit and scope of the invention as defined in the appended claim.

Referring now to the illustrations, 4, represents an axle encircled by a drum, 5, secured thereon by a key, 6, or otherwise. The drum serves as a journal upon which freely rotates a collar or hub 7. Relative displacement of the hub and journal is prevented by means of a plate, 8, on the outer

face of the wheel and a ring, 9, on the inner face, the ring and plate being secured to the hub by means of bolts, 10, which pass through the plate, hub and ring.

The journal is formed with a reduced portion, 11, flush with the inner face of and encircled by the ring. To the said reduced portion is secured a plate, 12, which overlaps the ring and serves to prevent leakage of lubricant between the ring and the reduced portion of the journal. 13, is the rim of the wheel which may be of any preferred construction and secured to the hub, 7, by double spokes each comprising a pair of separate members, 14.

The outer end portion of each of the members, 14, is bent toward the companion member as at 15. The said portions of each pair overlap each other and are preferably removably secured to the rim 13, by bolts, 16.

The spoke members diverge in the direction of the hub, and the inner end portion of each member is bent toward the companion member, as at 17. The said inner end portions of each pair overlap each other and are secured to the hub by cap screws 18.

To prevent dishing of the wheel, or unturning of the cap-screws, the hub is encircled by an open clamping band, 19, which passes between the spokes, and is provided with slots, 20, to receive the heads of the cap-screws and permit the band to be bound firmly against the overlapping ends of the spokes.

The ends of the band are provided with radially disposed ears, 21, interconnected by a bolt, 22, by means of which the band is tightened.

The diameter of the drum, or journal, is preferably slightly greater than the radius of the wheel, thereby reducing the tendency of the wheel to twist the axle.

It is evident the wheel is inexpensive in construction and may be assembled by unskilled labor.

Obviously, roller bearings may be interposed between the hub and journal if desired.

Having thus described my invention, what I claim as new and desire to secure by Letters Patent of the United States, is—

A wheel including a hub, a rim, double

spokes, each including a pair of elongated elements having their outer ends secured to the rim, said elements being separated from each other adjacent the hub, the inner end 5 portions of said elements being bent laterally, overlapped with each other, and provided with registering bolt holes, cap-screws penetrating said holes and threaded into the hub, and a clamping band encir-

eling the hub, impinging said overlapped portions, and provided with openings enclosing the cap-screw heads to prevent turning of the same.

In testimony whereof, I have hereunto set my hand this 26th day of December, 1916.

HENRY WILLIAMS.
